UNITED STATES PATENT OFFICE.

WILLARD F. RICHARDS, OF DEPEW, NEW YORK, ASSIGNOR TO GOULD COUPLER COMPANY, OF NEW YORK, N. Y.

RAILWAY DRAFT APPLIANCE.

1,235,726.

Specification of Letters Patent. Patented Aug. 7, 1917.

Application filed March 24, 1913. Serial No. 756,331.

To all whom it may concern:

Be it known that I, WILLARD F. RICHARDS, a citizen of the United States, residing at Depew, in the county of Erie and 5 State of New York, have invented a new and useful Improvement in Railway Draft Appliances, of which the following is a specification.

This invention relates to railway draft 10 appliances and more particularly to the draft yokes or devices by which the car couplers are connected to the yielding or spring resistance mechanisms of the draft gears.

15 In railway draft and buffing gears of the kind commonly in use at the present time a yoke or strap attached to the inner end of the drawbar or shank of the coupler extends around the spring or resistance mechanism of the draft gear for transmitting the draft from the coupler to the resistance mechanism. These yokes are ordinarily arranged vertically between the draft beams of the car, that is, with the upper and lower 25 bars of the yoke above and below the resistance mechanism of the draft gear. If the yoke is attached to the coupler shank by vertical bolts or rivets, as is commonly the case, it is a matter of great difficulty and

30 in some cases an impossibility to remove the coupler from the car without taking out the draft gear. It has been attempted to detachably connect the yoke to the drawbar or coupler shank in such a way as to 35 allow the coupler to be disconnected from the yoke and removed, leaving the yoke with the resistance mechanism of the draft gear in place on the car, this being done by means of a connecting pin or key which ex-

40 tends horizontally through registering holes in the coupler shank and portions of the yoke disposed at opposite sides of the coupler shank and is removable through holes in the draft beams of the car. In order to 45 provide the necessary parts at the opposite vertical sides of the coupler shank for the engagement of the horizontal connecting pin, the yokes have been cast with an integral socket to receive the end of the coupler shank, or with integral side walls which 50 embrace the coupler shank. These cast steel yokes are objectionable for the reason that it is exceedingly difficult, if not impracticable, to make the cast steel yokes

55 of uniform tensile strength and quality.

The yokes frequently contain hidden gas holes or flaws which weaken them and they are apt to be weak at the juncture of the strap with the socket on account of the unequal shrinkage of these different 60 parts.

The object of this invention is to produce a practical and desirable draft yoke of strong, durable and economical construction which is provided at its outer end with 65 a socket or part, adapted to receive the inner end of the coupler shank or drawbar, and to be connected thereto by a horizontal removable key or device which permits the coupler to be detached from the yoke and removed from the car leaving the yoke and resistance mechanism of the draft gear in 70 place on the car.

This is accomplished by making the yoke of a wrought metal strap adapted to surround the resistance mechanism of the draft gear, and a socket or part, preferably made of cast steel, which is securely attached to the strap and in which the coupler shank or drawbar is removably secured by the 75 horizontal cross key or other device permitting the coupler to be readily detached from the yoke.

In the accompanying drawings:

Figure 1 is a plan view of the draft yoke 85 embodying the invention and the inner end of the coupler shank or drawbar to which it is connected.

Fig. 2 is a side elevation, partly in section, 90 thereof.

Fig. 3 is a transverse sectional elevation thereof in line 3—3, Fig. 1.

Like reference characters refer to like parts in the several figures.

A represents the inner end of the coupler 95 shank or drawbar which may be of the usual or any suitable construction, the inner end of the shank being provided with a transverse horizontal pin or key hole a.

The yoke consists of a strap B of substantially 100 U-shape which is made of wrought iron or steel and is adapted to pass around the spring or resistance mechanism of the draft gear (not shown) in the usual manner, and a socket or part C, preferably of cast 105 steel, which is attached to the forward or outer end of the strap B and is adapted to receive and be detachably secured to the inner end of a coupler shank or drawbar A, preferably by the usual horizontal cross key 110

or pin D which passes through the hole *a* of the coupler shank and through register holes *c* in the upright side walls or portions of the socket C. The socket C is of a size to permit the inner end of the coupler shank to be readily slipped endwise into and out of the same, and as shown it consists of opposite upright side walls or plates *c'* and horizontal top and bottom walls or plates *c''* which join the upper and lower portions of the side walls at the inner portion of the socket. The ends of the upper and lower bars of the strap B are preferably confined in recesses *c³* in the inner faces of the top and bottom walls of the socket, and are provided, respectively, with upwardly and downwardly bent extremities *c⁴* entering correspondingly shaped holes *c⁵* in the top and bottom walls of the socket. The inner end of the coupler shank or drawbar when in place in the socket C extends between the ends of the bars of the strap B which are spaced apart a distance substantially equal to the depth of said inner end of the shank, and the shank is, therefore, adapted to prevent the bars of the strap from springing toward each other so as to disengage the extremities *c⁴* of the strap from the holes *c⁵* in the top and bottom walls of the socket. While the coupler shank thus serves as a means to prevent the disconnection of the strap from the socket or casting C and is adequate for this purpose under normal conditions, for the sake of additional security the ends of the strap are preferably permanently fastened to the socket C in such a way as to positively prevent the strain on the strap from straightening out or breaking the extremities *c⁴* and thus tearing the strap away from the socket. This is conveniently done by upsetting the extremities *c⁴* or otherwise making them of increased cross section with diverging sides whereby they are securely interlocked in the holes *c⁵* and cannot be broken or straightened and pulled out of the holes *c⁵*. This interlocked connection can be readily formed in casting the socket C by placing the strap B in the mold for the socket and pouring the metal for the socket into the mold about the yoke or strap. In this way the ends of the strap fit tightly in the recesses *c³* and holes *c⁵* of the top and bottom plates of the socket and are permanently and securely attached thereto. The metal of the top and bottom plates will also flow more or less under the upturned and downturned extremities of the strap, as indicated at *c⁶*, and further assists in preventing the ends of the strap from being disengaged from the holes *c⁵*. The strap is thus permanently attached to the socket

or casting without the use of rivets or any other separate securing devices, the connection being in this respect an economical and reliable means of securely fastening the strap to the socket or casting. The described connection has the further advantage over rivets or the like fastenings, in that the strap and top and bottom walls of the socket are not weakened by holes for the fastenings and there are no parts to work loose or break.

The side walls *c'* of the socket C are preferably formed with projecting bosses *e*, surrounding the pin or key holes *c*, which strengthen the side walls and afford broad bearings for the connecting pin or key D, and also with strengthening ribs *e'* which diverge rearwardly from the forward ends of the bosses *e* to the upper and lower edges of the side walls and thus serve to transmit the stress from the connecting pin or key to the top and bottom walls of the socket to which the bars of the strap are attached.

The construction described provides a secure and safe connection between the coupler shank or drawbar and the yoke, which permits the coupler to be readily detached from the yoke and removed from the car, and the yoke is strong and durable and can be cheaply manufactured.

I claim as my invention:

1. A draft yoke for car couplers, comprising a cast metal socket adapted to receive and be detachably secured on the shank of a car coupler, and a wrought metal strap, the ends of which extend in between the coupler shank and the walls of said socket and are provided with projections, said socket having integral portions thereof which embrace and tightly fit the ends of said strap and interlock with said projections of the strap to prevent movement of said strap in any direction relatively to said socket and permanently secure the strap to the socket.

2. A draft yoke for car couplers, comprising a hollow socket adapted to receive and be detachably secured to the shank of a car coupler, and a metal strap, the legs of which lie against the inner faces of the walls of said socket and have outwardly bent ends which extend into holes in the walls of said socket and have outer extremities of greater dimensions than the inner ends of said holes whereby said strap is permanently secured to said socket.

Witness my hand, this 21st day of March, 1913.

WILLARD F. RICHARDS.
